UNITED STATES PATENT OFFICE.

WILLIAM A. RICHARDSON, OF CORSICANA, TEXAS.

BOAT.

No. 839,321.

Specification of Letters Patent.

Patented Dec. 25, 1906.

Application filed December 26, 1905. Serial No. 293,301.

To all whom it may concern.

Be it known that I, WILLIAM A. RICHARDSON, a citizen of the United States, residing at Corsicana, in the county of Navarro and State of Texas, have invented new and useful Improvements in Boats, of which the following is a specification.

This invention relates to boats.

A boat involving my invention can be employed with utility for a variety of purposes, it being of particular adaptability by sportsmen, as it is of such a character that it can be submerged or lowered rapidly in the water to any desirable extent—for example, until its upper side or deck is even with the level of the water, so as to be hidden as nearly as possible from the view of water-fowl. The boat can be as rapidly raised. I attain the advantages by a novel construction which is simple to make. The boat may carry one or more persons. It may be made from any desirable material and may be propelled in any desirable way, such as by oars or a paddle.

In order to enable those skilled in the art to practice the invention, I will describe in detail a simple form of embodiment of the invention which is fully illustrated in the drawings accompanying and forming a part of this specification. The novelty of the invention will be included in the claims succeeding such description.

In said drawings, Figure 1 is a top plan view of a boat involving my invention, with a portion thereof removed. Fig. 2 is a side elevation with the intermediate portion of the boat removed. Fig. 3 is a cross-section on the line 3 3, Fig. 2. Fig. 4 is a similar view on the line 4 4 of Fig. 2.

Like reference characters refer to like parts throughout the several views.

A boat involving my invention may be of any desirable shape and may be made of any suitable material. The boat is represented as being of double-pointed form, and it may be made from sheet metal. These features, however, are immaterial, the same statement applying also to the way in which the boat is propelled, for it may be not only driven through the water by hand, but power carried by the boat may be used for such purpose.

The boat is represented as composed of two shells, as 2 and 3, connected together in such way as to present an air-chamber, as 4. In the present case this air-chamber is lo-

cated between the inner shell 2 and the outer shell 3. As will hereinafter appear, water is admitted into this chamber 4 for the purpose of submerging the boat, and to prevent the water in the air-chamber from shifting laterally I may employ a partition, as 5, extending longitudinally of the air-chamber and dividing the latter into two equal compartments. The presence of the partition reduces to the least possible extent the tendency of the boat to tip or rock sidewise when submerged.

The boat has a cockpit or dry compartment, which may be occupied by one or more persons. The boat represented is intended to be occupied by but one person. Around the entrance of the cockpit is an annular flange 5^a, about which I prefer to place an air-belt, as 5^b, of tubular construction, and which may be inexpensively made from metal and fixedly held in place in any suitable way.

The boat has an inlet for water opening into the air-chamber thereof, and this inlet may be located at any desirable point—for example, in the bottom, where it is shown in the drawings and designated by 6. This inlet may be valveless or may, as shown, be provided with a valve, as 6^a, the stem of which is represented as extended upward through the boat and deck thereof and as having at its upper end an operating-piece, as 6^b, by which said valve may be opened and closed.

In addition to the inlet for water the boat has an outlet for air, which outlet in the present case is presented by the valve-casing 7, fitted into the deck of the boat. It will be assumed that the air-chamber 4 is filled with air—that is, there is no water therein, the valve in the casing 7 at this time being closed. To submerge the boat, the valve in the casing 7 will be opened, thereby permitting air in the chamber 4 to exhaust into the atmosphere. The valve 6^a, if closed, will be also opened, and when this takes place water will rush into the air-chamber to cause the submergence of the boat, and when the latter has sunk to the desired extent the occupant of the boat will close the two valves. The boat may, as will be understood, be lowered until its deck is level with or even below the surface of the water.

I provide means for expelling the water from the air-chamber 4 to permit the boat to rise when this becomes necessary, and the means shown for accomplishing this result

will now be described. I have shown a nipple, as 8, fitted into the deck of the boat and containing an inwardly-opening spring-valve. This nipple constitutes an inlet for air into the chamber 4. To force air into the air-chamber 4 to expel the water therefrom, I have shown a pump, as 9, within the cockpit of the boat and which is ordinarily foot-operable, although it may be actuated by hand or power. The pump 9 is connected with the nipple 8 in any desirable way—for example, by the flexible tubing 10. The boat can be at once raised, when submerged, by the operation of the pump. When the pump is in action, the valve in the casing 7 at this time being closed and the valve 6^a, if present, being open, it serves to drive the water from the air-chamber 4 out through the hole 6.

20 The hole or inlet 6 is made sufficiently large as to secure rapid submergence of the boat when the valve in the casing 7 is opened. By the operation of the pump 9 the boat can be as quickly raised. The inlet or hole 6 in the bottom of the boat serves also as a water-outlet. The air-pressure in the chamber 4 resists the outside pressure acting against the boat, and the same result follows when there is water or water and air in said chamber. 25 30 By lowering the boat to the requisite extent it will be an easy matter for a sportsman to get within close range of water-fowl.

In connection with the boat I may employ at opposite sides thereof buoyant elements or floats, as 11. When the boat is submerged, 35 these floats dip into the water and hold the boat on an even keel. Their presence is not absolutely necessary, although they are of advantage when the occupant of a boat is of 40 a timid nature. The buoyant elements or floats are shown as arranged in pairs at opposite sides of the boat, overhang said sides, and may be connected to the boat in any desirable way. They may be of any shape, although a conical form is a satisfactory one. 45 When the boat is submerged its maximum extent, the upper edges of these floats will be slightly above the level of the water. From what has been stated it will be understood 50 that the floats are normally not in the water.

From the valve-casing 7 a tube 7^a depends downward into the air-chamber 4, and the lower edge of the tube is situated below the under side of the deck to prevent the level 55 of the water in said air-chamber reaching to the deck. By this means I always retain in the chamber 4 a body of air.

From what has been hereinbefore stated it 60 will be understood that my boat comprises two shells, what may be considered a main shell and an auxiliary shell. The main shell 3 in the present case consists of a hull and a deck over the same, the auxiliary shell 2 extending through said deck and toward the 65 bottom of the hull. The auxiliary shell 2

presents interiorly a cockpit for the occupant or occupants of the boat, and the various valves and pump may be readily controlled by the person or persons within said cockpit. The stem of the valve 6^a extends 70 through the deck, and the handle or operating-piece 6^b for said valve is within access of the said occupant or occupants, as is the valve-casing 7. The pump 9 is within said cockpit. The air-belt 5^b, surrounding the 75 upper external portion of the shell or cockpit 2, overlies the deck.

What I claim is—

1. A boat comprising a shell composed of a hull and a deck, and a second shell extending 80 through the deck and toward the bottom of the hull, said hull having an opening for the entrance of water and said second shell constituting a cockpit for the boat.

2. A boat comprising a shell composed of a 85 hull and a deck, a second shell extending through the deck toward the bottom of the hull and constituting the cockpit of the boat, a dividing-partition disposed between the deck and bottom of the hull, extending longitudinally of the boat and separating the interior of the boat into two non-communicating chambers.

3. A boat comprising a shell composed of a hull and a deck, a second shell extending 95 through the deck and toward the bottom of the hull, and an air-belt surrounding the upper portion of said second shell and overlying said deck, said second shell constituting a cockpit for the boat.

4. A boat comprising a shell composed of a hull and a deck, a second shell extending through the deck and toward the bottom of the hull, an air-belt surrounding the upper portion of said second shell and overlying 105 the deck, said second shell constituting a cockpit for the boat combined with floats normally outside of the water and extending laterally from opposite sides of the boat.

5. A boat comprising a shell composed of a 110 hull and a deck, a second shell constituting a cockpit and extending through the deck toward the bottom of the hull, a dividing-partition disposed substantially centrally and longitudinally of the first shell within 115 the same and dividing the boat interiorly into non-communicating chambers, an air-belt around the upper portion of the second shell, overlying said deck, and floats normally out of the water and extending laterally from opposite sides of said first-mentioned shell.

6. A boat comprising a shell composed of a hull and a deck, a second shell extending 125 through the deck and toward the bottom of the hull, said second shell constituting a cockpit for the boat, said first shell having a hole for water entering into the interior of the boat, and means for exhausting air from such interior to permit water to enter there- 130

into and for also expelling the water from said interior.

7. A boat comprising a shell composed of a hull and a deck, a second shell extending through the deck and toward the bottom of the hull and constituting a cockpit for said boat, the two shells presenting an air-chamber within the boat, a valved air-vent in said deck, said hull having a hole for the entrance of water opening into said air-chamber, and a valve for said hole provided with a stem extending through said deck and having a handle above the deck.

8. A boat comprising a shell composed of a hull and a deck, a second shell extending through the deck and toward the bottom of the hull and constituting a cockpit for said boat, the two shells presenting an air-cham-

ber within the boat, a valved air-vent in said deck, said hull having a hole for the entrance of water opening into said air-chamber, a valve for said hole provided with a stem extending through said deck and having a handle above the deck, and an air-pump within said second shell provided with a conduit extending threfrom and through the deck to provide for the expulsion of water from said air-chamber by the action of said pump.

In testimony whereof I have hereunto set my hand in presence of two subscribing witnesses.

WILLIAM A. RICHARDSON.
